CLAIM

The ornamental design for a “beverage bonnet”, as shown and described.

DESCRIPTION

FIG. 1 is an elevation view of the “beverage bonnet”

FIG. 2 is a top view of the “beverage bonnet”; and,

FIG. 3 is a bottom view of the “beverage bonnet”. The broken lines in the FIGS. 1 and 2 of the drawings represent unclaimed environmental subject matter and form no part of the claim.

Any shading and cross hatching are not features of the design and are utilized to illustrate the surface contours of the “beverage bonnet” design in the drawings.
